UNITED STATES PATENT OFFICE

106,816

DESIGN FOR A PINKING MACHINE

Harry C. Herschman, Wheaton, Ill., assignor to
Apex Pinking Machine, Inc., Chicago, Ill., a
corporation of Illinois

Application July 2, 1937, Serial No. 70,239

Term of patent 14 years

To all whom it may concern:

Be it known that Harry C. Herschman, a citizen of Russia, residing at Wheaton, in the county of Du Page and State of Illinois, has invented a new, original, and ornamental Design for Pinking Machine, of which the following is a specification.

Referring to the drawing forming a part of the specification thereof,

Figure 1 shows a front perspective view of a machine embodying the new design, and Figure 2 shows a rear perspective view thereof on a slightly smaller scale.

I claim:

The ornamental design for a pinking machine, as shown.

HARRY C. HERSCHEMAN.
